UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

ROTARY MAGAZINE FOR LOOMS.

1,325,207.

Specification of Letters Patent. Patented Dec. 16, 1919.

Application filed May 27, 1919. Serial No. 300,087.

To all whom it may concern:

Be it known that I, ALONZO E. RHOADES, a citizen of the United States, residing at Hopedale, county of Worcester, and State 5 of Massachusetts, have invented an Improvement in Rotary Magazines for Looms, of which the following description, in connection with the accompanying drawings, is a specification, like characters on the drawings representing like parts.

The present invention relates to improvements in the rotary magazines of weft replenishing looms, such magazines being adapted to hold a large number of weft carriers or bobbins which are to be transferred one by one into the working shuttle; and the improvements more directly relate to the means for maintaining the bobbin engaging ends of the heads of the magazine in 15 alinement parallel with the axis of the shuttle to which the weft carriers or bobbins are to be transferred. Heretofore, the heads of the rotary magazine were mounted upon a support for rotative movement to carry the 20 filling carriers or bobbins one by one to the transfer position, at which time, the longitudinal axis of the bobbin which is to be transferred to the shuttle must be parallel to the longitudinal axis of the shuttle, otherwise damage is liable to result either to the 25 shuttle or carrier or other parts of the loom. Such rotary magazines are usually designed to have the heads thereof adjustable relatively toward or away from each other to 30 adapt the magazines to bobbins or filling carriers of different lengths, but when the heads have been thus adjusted, the alinement of the bobbin end engaging means on the two heads are liable to be accidentally 35 moved out of their alined position, with the result that when a filling carrier or bobbin is positioned for transfer its axis would not coincide with or be parallel to the longitudinal axis of the shuttle, and damage would 40 result as above indicated.

In accordance with the present invention, the rotary magazine has the heads adjustable toward and from each other as required, and means are provided to prevent relative 45 movement of the heads of the magazine during the time the heads are adjusted

toward and from each other, the result being that the bobbin end engaging means carried by the two heads remain in their original alinement parallel to the longitudinal axis 55 of the shuttle into which the filling carriers are to be transferred.

In accordance with another feature of the present invention, the parts of the magazine are so formed and related and connected to 60 the rotary thread guide that when the rotary thread guide is removed from the magazine, one of the bobbin holding heads of the magazine may be removed with it without disturbing the relative rotative position of 65 the head and the rotary thread guide with which it is associated.

Other features of the invention in addition to the above will hereinafter be described in connection with the accompanying 70 drawings which illustrate one good practical form of the invention, and then the novel characteristics and combinations will be described by the claims.

In the drawings:

Figure 1 is a vertical longitudinal section of a rotary magazine for filling replenishing looms containing the present invention;

Fig. 2 is a transverse section on the line 2—2 of Fig. 1.

In its general features the rotary magazine and its coöperating relation with other features of filling replenishing looms may be generally similar to the well known Draper or Northrup loom, as illustrated, for 85 example, by Letters Patent of the United States, No. 529,940, November 27, 1894, and upon such general features of the rotary magazine the present invention improves.

As indicated in the accompanying drawings, 1 is a stand or bracket fixed to a stationary part of the loom, and in the present instance it is formed as a disk-like member in which is mounted the supporting stud 2. The supporting stud 2 is provided with a 95 shoulder 3 which bears against the hub-like portion 4 of the stand, and the outer end portion 5 of the supporting stud is provided with screw threads on which is placed the clamping nut 6 whereby the supporting 100 stud is held in fixed position relative to the stand 1.

The supporting stud 2 may be variously contrived, but as indicated in the present instance, it has the barrel-like portion 7 and the extended end portion 8 on which is mounted for rotation the elongated sleeve 9, against the end 10 of which a washer 11 rests under the clamping action of the nut 12 threaded to the end of the stud 2, the construction being such that the sleeve 9 may be 5 rotatively supported upon the supporting stud, a shoulder 13 affording one good suitable means for preventing relative longitudinal movement of the sleeve on the stud.

The sleeve 9 is provided with a large interior chamber 14 surrounding the large cylindrical part 7 of the stud and affording an oil receptacle for the transmission of lubricant between the sleeve and stud. The stud 2 is provided with a longitudinally extending duct 15 and a radial portion 16 communicating with the large interior chamber 14. Exterior to the duct 15 is an oil receiver 17 having communication with the duct 15 for the transmission of oil to the 20 large chamber 14 of the sleeve.

One of the heads of the magazine is rigidly connected with the sleeve 9. In the present instance of the invention, the head 18 which is provided with sockets 19 or other 30 means for engaging the butt ends of the bobbins is rigid with the sleeve 9, preferably by being formed integral therewith, it being obvious, of course, that the rigid connection between the sleeve and head may be otherwise contrived. The head 18 may be provided with the usual ratchet teeth or other means 20 for giving rotary movement of the head and sleeve as the filling carriers or bobbins are moved to transferring position.

The elongated sleeve 9 has an end portion 21 of reduced diameter forming a shoulder 22 against which bears one end of the elongated hub 23 carrying the rotary thread guide 24. The rotary thread guide and its hub 23 are suitably connected to the sleeve 9 to rotate therewith by appropriate means, which in the present instance of the invention, consists of a clamping screw 25 passing through the hub 23 and engaging a substantially flat surface 26 on the sleeve, the construction being such that when the parts are assembled as indicated, the bobbin end engaging means on the two heads of the 55 magazine will be held in alinement with the axes of the bobbins parallel with the longitudinal axis of the shuttle.

The other head of the magazine indicated at 27 is provided with a series of bobbin end 60 engaging means for engaging the tip ends of the bobbins. In the present instance these are shown as the yielding fingers 28 which may be of usual construction. The magazine head 27 is mounted on the extended hub portion 23 of the rotary thread

guide, and the hub 29 of the magazine head 27 is provided with a key-way 30. The extended hub 23 is similarly provided with a key-way 31, and a key 32 engages the key-ways of the hub and the head to prevent 70 relative rotative movement between the two, and permit longitudinal adjustment of the head 27 on the elongated hub 23 of the rotary thread guide.

When the magazine head 27 has been adjusted toward and from the opposing head 18 in accordance with the requirements of the bobbins being used, it may be clamped or held in such adjusted position by suitable means, such, for instance, as the clamping screw 33 which passes through the hub 29 of the head 27 and engages the elongated hub 23 of the rotary thread guide. The construction is such that when the rotary thread guide 24 and its hub 23 have been adjusted 85 and secured in position upon the sleeve 9, the bobbin end engaging means of the heads 18 and 27 will be in alinement to maintain the bobbins with their longitudinal axes parallel to the longitudinal axis of the shuttle. 90 If, now, it be desired to adjust the heads 18 and 27 relatively toward or from each other, it is only necessary to unclamp the screw 33 and move the head 27 longitudinally upon the hub 23 of the rotary thread guide, 95 and during such adjustment, the connection between the head 27 and the hub 23 of the rotary thread guide, maintains the head 27 from rotary movement relative to the head 18, with the result that the previously established alinement of the bobbin end engaging means which supports the bobbins with their axes parallel to the longitudinal axis of the shuttle, remains undisturbed. If it is desired to remove the rotary thread guide and 100 its connected magazine head 27, it is only necessary to manipulate the clamping screw 25, whereupon the rotary thread guide, the hub 23 and the head 27 may be removed as a unit.

The hub portion of the rotary thread guide may be provided with an enlarged socket 34 for the accommodation of the clamping washer and nut 11 and 12, and likewise with a longitudinal bore for the accommodation of the end 35 of a thread holder 36 about which the ends of the threads leading from the bobbins will be wound. A clamping screw 37 serves to secure the thread holder 36 to the rotary 115 thread guide.

What is claimed is:—

1. A rotary magazine for filling replenishing looms, having, in combination, a supporting stand and a laterally projecting supporting stud, a rotary head provided with a series of sockets for supporting the butt ends of bobbins, a sleeve extending from the rotary head and having an end portion of reduced diameter, a rotary thread guide hav- 120 125 130

ing an elongated hub portion mounted on the reduced end portion of the said sleeve, a second rotary head provided with a series of sockets for supporting the tip ends of 5 bobbins and mounted on the elongated hub portion of the rotary thread guide between the guide and said first rotary head, a key and slot connection between the elongated hub portion of the rotary thread guide and 10 second rotary head to permit the latter to be moved toward and from the other head to accommodate bobbins of different lengths while maintaining proper alinement of the 15 sockets in the two heads, a set screw for securing the second head in adjusted position on the hub of the thread guide, and a set screw for securing the rotary thread guide to the reduced end of the sleeve.

2. A rotary magazine for filling replenishing looms, comprising, in combination, a supporting stand and a supporting stud, a rotary head having an elongated sleeve mounted for rotary movement on the supporting stud, a rotary thread guide having 25 an elongated hub portion mounted on said elongated sleeve, a second rotary head having a key and slot connection with the hub of the rotary thread guide to permit adjustment of the second head toward or from 30 the first mentioned head while maintaining the two heads from relative rotative movement and the bobbin holding means on the two heads in undisturbed alinement, means for securing the second rotary head in adjusted position longitudinally on the elongated hub of the thread guide, and means for securing the thread guide to the elongated sleeve.

3. A rotary magazine for filling replenishing looms, comprising, in combination, a supporting stud, a rotary head having an elongated sleeve mounted for rotary movement on the supporting stud, a rotary thread guide having an elongated hub portion 45 mounted on the elongated sleeve, means for detachably securing the hub and sleeve together to prevent subsequent relative rotative movement thereof, a second head mounted on the hub of the thread guide, 50 means permitting adjustment of the second head longitudinally along the hub but preventing relative rotative movement of the second head and thread guide as the second head is adjusted toward or from the first 55 rotary head, and means for securing the second head to the hub in adjusted position.

4. A rotary magazine for filling replenishing looms, comprising, in combination, a supporting stand and stud, an elongated 60 sleeve mounted for rotative movement on the supporting stud, a bobbin carrying head rigidly connected to the elongated sleeve for rotative movement therewith and having a series of bobbin butt engaging means, a second 65 rotary head carried by the elongated

sleeve and having a series of bobbin tip engaging means that a series of bobbins may be supported between said heads with the axes of the bobbin in parallel relation to the axis of the active shuttle, and connections between the elongated sleeve and the second rotary head permitting adjustment of the second rotary head toward and from the first rotary head while preventing relative rotative movement of the two heads during such adjustment that the longitudinal axes of the bobbins in the magazine may be maintained parallel to the axis of the active shuttle.

5. A rotary magazine for filling replenishing looms, having a stand and supporting stud, a sleeve mounted for rotative movement on the supporting stud, two heads having bobbin end engaging means for supporting a series of bobbins between them 70 with the axes parallel to the axis of the active shuttle, one of said heads being rigidly connected to the sleeve, a thread guide having an elongated hub mounted on the elongated sleeve, and provided with a key-way, the other of said heads having a hub portion mounted on the elongated hub of the thread guide and provided with a key-way, a key engaging the said key-ways of the thread guide and head permitting relative adjustment of the two heads toward and from each other while preventing relative rotative movement and maintaining alinement of the bobbin engaging means on the two heads parallel with the axis of the 80 active shuttle, means for securing the said other head in adjusted position on the elongated hub of the thread guide, and means for detachably securing the thread 85 guide to the sleeve.

6. A rotary magazine for filling replenishing looms, comprising, in combination, a supporting stud, an elongated sleeve mounted for rotative movement on the stud, two heads having bobbin end engaging 90 means for supporting a series of bobbins between them with their axes parallel to the axis of the active shuttle, said heads being rotatable with the sleeve, and connections between one of the heads and elongated 95 sleeve permitting the head to be adjusted toward or from the other head while preventing relative rotative movements of the two heads during such adjustment that the longitudinal axes of the bobbins in the 100 magazine may be maintained parallel to the axis of the active shuttle.

7. A rotary magazine for filling replenishing looms, having a stand and supporting stud, a sleeve rotatably mounted on the 110 stud, a thread guide having an elongated hub mounted on and to rotate with the sleeve, two heads having bobbin end engaging 115 means, one of said heads being rigid with the rotary sleeve and the other head 120

being mounted on the hub of the thread, the
guide, means permitting the said other head
to be adjusted toward and from the thread
guide and preventing relative rotative move-
ment of the head and thread guide during
said adjustment, and means for detachably
connecting the elongated hub of the thread

guide to the rotary sleeve permitting the
thread guide and said other head to be re-
moved from the sleeve as a unit without dis- 10
turbng their rotative relation.

In testimony whereof I have signed my
name to this specification.

ALONZO E. RHOADES.
